Primary Examiner — Cynthia Ramirez*Assistant Examiner* — L. Martinez-Rivera(74) *Attorney, Agent, or Firm* — Andrew F. Young, Esq.; Lackenbach Siegel, LLP(57) **CLAIM**

The ornamental design for a jewel setting, as shown and described.

DESCRIPTION

FIG. 1 is a front top perspective view of a jewel setting of a first embodiment of our present invention.

FIG. 2 is a bottom rear perspective view thereof.

FIG. 3 is a top plan view thereof.

FIG. 4 is a bottom plan view thereof.

FIG. 5 is a front side elevation view thereof.

FIG. 6 is a rear side elevation view thereof.

FIG. 7 is a left side elevation view thereof.

FIG. 8 is a right side elevation view thereof.

FIG. 9 is a front top perspective view of the jewel setting of second embodiment of our present invention.

FIG. 10 is a top plan view thereof.

FIG. 11 is a bottom plan view thereof.

FIG. 12 is a front side elevation view thereof.

FIG. 13 is a rear side elevation view thereof.

FIG. 14 is a left side elevation view thereof; and,

FIG. 15 is a right side elevation view thereof.
